[57] CLAIM

The ornamental design for an aircraft having a raised and rearward positioned cockpit, as shown and described.

DESCRIPTION

FIG. 1 is a perspective view of an aircraft having a raised and rearward positioned cockpit according to my new design;

FIG. 2 is a left side elevational view of FIG. 2, the right side being a mirror image thereof;

FIG. 3 is a front elevational view of FIG. 1;

FIG. 4 is a top plan view of FIG. 1; and,

FIG. 5 is an enlarged fragmentary left side elevational view of FIG. 1, the left side being a mirror image thereof; and, FIG. 6 is an enlarged fragmentary top plan view of FIG. 1. Those portions shown in dotted and phantom lines are for illustrative purposes only and form no portion of my claimed design.

1 Claim, 5 Drawing Sheets

FIG. 2.

FIG. 3.
